UNITED STATES PATENT OFFICE

JOHN F. COLEMAN, OF SHARON, MASSACHUSETTS; ALICE M. COLEMAN, EXECUTRIX OF SAID JOHN F. COLEMAN, DECEASED, ASSIGNOR TO COLEMAN BROTHERS, INC., OF BOSTON, MASSACHUSETTS, A CORPORATION OF MASSACHUSETTS

TRASH DISPOSAL PLANT

Application filed June 11, 1928. Serial No. 284,456.

This invention relates to apparatus for the handling and sorting of refuse materials (excluding garbage) such as are collected in large cities.

Refuse of this character includes (1) fine materials such as dirt and ashes, suitable for use in filling and grading work; (2) marketable materials such as some metals, glass, paper, rags, etc., and (3) worthless materials and trash which may largely be disposed of by incineration, providing steam for power purposes.

It is the object of the present invention to devise a plant so arranged as to facilitate the efficient separation of the refuse into the three above mentioned classifications.

In order that the invention may be readily understood, reference is had to the accompanying drawings forming part of this specification, and in which:

Fig. 1 is a side elevation showing the essential features of a plant constructed in accordance with the invention, parts being illustrated in section;

Fig. 2 is a plan view of the same, parts also being shown in section;

Fig. 3 is a sectional elevation, substantially on the line 3—3 of Figure 1, looking in the direction of the arrows; and

Fig. 4 is a fragmentary perspective view showing a part of the separating mechanism.

Referring to the drawings in detail, the improved plant comprises a suitable enclosure 1 having a roof 2, this roof preferably being extended as shown at 2^a in Fig. 1, so as to form a shed covering portions of the apparatus outside of the enclosure.

Just outside the enclosure is provided an elevated platform 3, best shown in Fig. 3, on to which the trucks or wagons loaded with trash are driven by means of an inclined runway (not shown). At the edge of this platform is provided a stop rail 4, so that the vehicles can be backed against this stop rail in position to be dumped.

Extending downwardly from this stop rail is an inclined grid or sieve designated in its entirety by the reference numeral 5, and formed of a series of spaced parallel bars. As shown, this grid is preferably set

at an angle of approximately 30° to 40°, and the material dumped from the truck or wagons tends to flow by gravity down this grid.

Owing to the nature of the material being handled, however, I find it desirable to provide means in addition to gravity for causing the material to move along the grid and for agitating such material so as to separate or sift out the fine portions, suitable for filling or grading use. This means consists of a series of groups of fingers 6 mounted on cross bars or slats 7 (see Fig. 4) secured to a pair of sprocket chains 8 passing over sprocket wheels 9, mounted upon upper and lower shafts 10. These elements constitute what I have called an endless carrier, and this carrier is so arranged that its upper run extends parallel with and just beneath the grid 5, as clearly shown in Fig. 3, with the fingers 6 projecting up through the spaces between the bars in such a manner as to engage the material resting on the grid.

The carrier is driven by suitable means such as a sprocket 11 secured to the upper shaft 10 and caused to rotate by means of a chain 12 operatively associated with an electric or other suitable motor 13. It will be observed that the direction of drive is such that the upper run of the carrier moves downwardly along the grid, as shown by the arrow in Fig. 3, thus aiding gravity in causing the material to progress downwardly over the grid.

Adjacent the bottom of the grid I provide a transversely extending trough or chamber 14 in which is mounted a suitable endless conveyor 16, preferably having projecting fingers 17 or the like. This conveyor is supported at one end on sprocket wheels 18 and comprises a horizontal portion extending from this end for a distance equal to the width of the grid. The conveyor then passes around guide sprockets 19 and extends upwardly over guide sprockets 20 around another end sprocket 21, the portion between the sprockets 20 and 21 being also horizontal. This conveyor is driven by any suitable motor (not shown).

The trough or chamber 14 in which the lower horizontal run of the conveyor is

housed is provided with a sectional cover preferably comprising a series of independent removable boards 15. The purpose of this cover is to prevent the conveyor from becoming clogged by the material being delivered on to it too rapidly. In operation, one or more of the boards 15 is removed and the coarse material or oversize from the grid is delivered to the conveyor 16 by being fed through the opening or openings thus formed, it being understood that an attendant stands upon or near the cover boards 15 and feeds the material through the openings by means of a pitchfork or other suitable implement.

It will be observed that the width of the grid is substantially the same as that of the platform 3 and is preferably at least as great as twice the width of the wagons or trucks being dumped so that a plurality of these vehicles can be driven side by side onto the platform and can be dumped alternatively at opposite sides of the grid, thus giving the attendant an opportunity to dispose of one load before another load is delivered. Room is thus provided in which more than one attendant can work at a time, if desired. The materials fed through the openings in the cover 15 on to the conveyor 16 are carried by the latter up to and along a sorting or picking table 22. By reference to Fig. 2, it will be seen that sorting bins 23 are preferably arranged on each side of the conveyor above this table, and a space is provided between these bins and the conveyor in which one or more attendants may stand and pick out and sort the marketable materials as they travel along the conveyor. The materials thus picked out are thrown into the respective sorting bins.

The materials remaining on the conveyor after picking and sorting fall from the conveyor on to the chute 25, and are delivered thence on to a platform 26 supported on a suitable furnace 28. Feed holes 27 are provided in the top wall of the furnace at each side of the platform 26, and in operation one or more attendants will stand on this platform and with a pitchfork or other suitable implement will feed the material down through the holes 27 into the furnace, it being understood, of course, that unusually large pieces of an incombustible character will be pushed aside.

Mounted in such a position as to be exposed to the heat of the furnace is a steam boiler 29, and the products of combustion finally escape through the stack 30. Steam from this boiler may be employed to drive a generating unit to furnish electric current for supplying the motors necessary for operating the several carriers and conveyors. Access to the sorting table 22 is afforded by suitable steps or ladders 24.

In order to collect the material suitable for

filling or grading use, which falls through the grid or sieve 5, I provide an inclined plate or chute 31 beneath this grid and arrange its lower end so as to deliver the material on to a conveyor 33 mounted in a trough or chamber 32. This conveyor, as clearly shown in Fig. 1, extends upwardly at one side of the grid and delivers into a storage bin 34.

From the foregoing it will be seen that I have provided a plant so arranged that trash may be readily separated; the portion suitable for filling use being stored in bins; the marketable portions being sorted and collected in bins, and the worthless portions being fed to a furnace, and it is thought that the many advantages of my invention will be readily appreciated by those familiar with the problem to which it relates.

What I claim is:—

1. A trash disposal plant comprising an elevated loading platform, transversely extended to accommodate side by side a plurality of loading units, a stationary grid transversely commensurate with the platform; a conveyor for oversize extending transversely of the lower edge of the grid, a platform adapted to sustain operatives, between said grid and conveyor and comprising removable sections overlying the conveyor, said sections being adapted to control the supply of oversize to the conveyor.

2. A trash disposal plant comprising an elevated loading platform, transversely extended to accommodate side by side a plurality of loading units, a stationary downwardly inclined grid transversely commensurate with the platform and enables means associated with said grid for agitating material dumped thereon and for facilitating movement of the material along the grid; a conveyor for oversize extending transversely of the lower edge of the grid, a platform adapted to sustain operatives, between said grid and conveyor and comprising removable sections overlying the conveyor, said sections being adapted to control the supply of oversize to the conveyor.

In testimony whereof I affix my signature.

JOHN F. COLEMAN.
